UNITED STATES PATENT OFFICE

100,927

DESIGN FOR A CHILD'S GARMENT

Miriam N. Shaffer, Cleveland, Ohio

Application June 29, 1936, Serial No. 63,566

Term of patent 14 years

To all whom it may concern:

Be it known that I, Miriam N. Shaffer, a citizen of the United States, residing at Shaker Heights, in the city of Cleveland, county of Cuyahoga, and State of Ohio, have invented a new, original, and ornamental Design for a Child's Garment, of which the following is a specification, reference being had to the accompanying drawing, wherein the figure is a front view of a child's garment showing my new design,

The characterizing feature of my design resides in a conventionalized representation of an animal as shown formed on the knee portions of the garment by the stitched outline of a reinforcing patch. The back of the garment is of conventional form.

I claim:

The ornamental design for a child's garment substantially as shown and described.

MIRIAM N. SHAFFER.
